Primary Examiner — T Chase Nelson*Assistant Examiner* — Kelly L Gross(74) *Attorney, Agent, or Firm* — Coloplast Corp., Coloplast A/S; Nick Baumann(57) **CLAIM**

The ornamental design for a base plate for an ostomy bag, as shown and described.

DESCRIPTION

FIG. 1 is a perspective view of a base plate for an ostomy bag;

FIG. 2 is a front elevation view of the base plate for an ostomy bag;

FIG. 3 is a back elevation view of the base plate for an ostomy bag;

FIG. 4 is a right side view of the base plate for an ostomy bag;

FIG. 5 is a left side view of the base plate for an ostomy bag;

FIG. 6 is a top side view of the base plate for an ostomy bag; and,

FIG. 7 is a bottom side view of the base plate for an ostomy bag.
